UNITED STATES PATENT OFFICE.

MATTHEW G. O'NEIL, OF DALLAS, TEXAS, ASSIGNEE, BY MESNE ASSIGNMENTS, TO
STANDARD VENDING CORPORATION, OF WILMINGTON, DELAWARE, A CORPORA-
TION OF DELAWARE.

VENDING MACHINE.

Application filed February 11, 1921. Serial No. 444,244.

The invention relates to an improvement in vending machines of the class wherein small articles such as gum, candy and the like are delivered from the machine upon 5 the deposit of a proper coin therein and the manipulation of a lever or plunger.

One object of the invention is to reorganize and improve the construction and arrangement of the parts constituting a vending machine of the above character in order to produce a machine simple and durable in construction, efficient in operation, and relatively cheap to manufacture. Another object of the invention is to produce a vending 15 machine in which the coin-controlled mechanism is carried entirely by the cover, which is hinged to the box or cabinet in which the goods or articles to be vended are contained. A further object of the invention is to so 20 form the parts of a vending machine of the above described character that they may be produced in quantity lots and be assembled with a minimum of adjustment. Other objects of the invention and the purposes there- 25 of will appear as the description proceeds. With these objects in view, the invention consists in the improved vending machine hereinafter described and particularly pointed out in the appended claims.

In the accompanying drawings illustrating the preferred form of the invention, Fig. 1 is a rear elevation of the operating mechanism of the improved vending machine, the view being a vertical section 35 through the cover; Fig. 2 is a view similar to Fig. 1, but taken from the opposite direction; Figs. 3 and 4 are sectional views taken on the lines 3—3 and 4—4, respectively, of Fig. 1; Fig. 5 is a front elevation of the 40 complete vending machine; Fig. 6 is a side elevation of the machine shown in Fig. 5, with a part broken away to show the connection between the operating parts carried by the cover and the article supporting tray; Fig. 7 is a perspective view of the machine 45 open, the coin tray being removed; Fig. 8 is a perspective of the coin tray; Fig. 9 is a perspective of the plates for supporting the operating mechanism; and Fig. 10 is a per- 50 spective of the lock for securing the coin lever in locked position.

In the illustrated embodiment of the invention the improved vending machine is shown as composed of a body part or box 1

in which the goods or articles to be vended are stored and a hinged cover 2, which contains the coin-controlled operating mechanism and the coin tray. By mounting the operating mechanism and the coin tray in the cover and utilizing the body portion or 55 box for containing only the articles to be vended, it will be recognized that the internal parts of the machine are easily accessible and that the machine may be replenished with goods and the coin tray emptied by 60 simply unlocking the cover and swinging it back on its hinges. So far as I am aware, this is the first time it has been proposed to construct a coin-controlled vending machine 65 in this manner. 70

The coin-controlled mechanism for actuating the means for supporting the articles to be vended is mounted between two plates 3 and 4 which are removably secured in position in the cover 2. The plates are 75 detachably secured together by means of interlocking tongues and recesses 15. A vertically-arranged locking bar 16 is provided with the notches 17 and 18 at its upper and lower ends, the bolt 20 passes through the 80 notch 18 and said notch is enlarged to permit the member 16 to slide while the bolt is in the notch. A knob 19 at the top of the bar serves to raise and lower the bar. The notch 17 engages with a pin 18^a fixed in the 85 upper part of one side of the box 1. The knob 19 passes through a slot in the cover 2 so that the bar 16 may be manipulated to disengage the cover from the box. A lip 16^a formed on the upper edge of the plate 90 3 is received under the downturned flange 17^a formed on the top side of the cover 2 and serves as additional means for securing the plates 3 and 4 in the cover. 95

The coin tray 22 rests on the bottom flange 100 of the cover in the open space beneath the plates 3 and 4. The rear end of the coin tray is provided with a lug 23 which is received beneath the tongue 25 extending downwardly from the plate 3; and the forward end of the coin tray is provided with an offset slotted flange 24 which receives the bolt 20 of the lock 21 secured to the inside of the bottom of the cover. When the cover is closed upon the box and the bolt 105 20 is shot, it passes through the flange 24 of the coin tray and the slotted flange 25^a on the box 1, thereby locking the coin tray.

in position and the cover to the box. The chewing gum, candy or other articles to be vended are contained within the box or cabinet 1 and supported in position on the tray 6 or cradle 26 pivotally mounted in the side walls of the box. One end of the tray 26 is provided with a toothed segment 27 which is adapted to be engaged by a part of the operating mechanism when the cover is closed on the box. When all the articles supported by the tray 26 have been delivered one at a time from the machine, a pivoted arm 29 falls forward and the upper forwardly projecting end 29^a thereof enters the slot 30 in the plate 3 and prevents additional coins from being inserted in the machine through the coin slot 31.

The coin-controlled mechanism for engaging and actuating the toothed segment 27 to tilt the tray 26 to deliver an article from the machine upon the deposit of a genuine coin therein, comprises a segment 8 mounted on a pin 12 journaled in the cover 2 (see Fig. 3). The forward end of the pin 12 projects through the outside of the cover and is provided with a butterfly nut or button 13 by which the coin-controlled mechanism is operated. A screw 14 passed through the plate 3 is received in the rear end of the pin 12 and acts to secure the pin and the parts carried thereby in operative position. The periphery of the segment 8 is provided with a series of notches 28 which are adapted to engage with the teeth of the segment 27 when the cover is closed on the box. A coin receiving arm or lever 9 is secured to the pin 12. When a coin of proper size and weight has been deposited in the machine, it is received in the notch 9^a of the lever 9. The button 13 is then turned to raise the lever 9 to bring the coin into engagement with the arcuate end 8^a of the segment 8. Thus, the arm or lever 9 and the segment 8 are operatively connected by the interposition of a coin. Interposed in the path of travel of the coin, while it is in the notch 9^a, is the inturned free end of a spring-like coin deflector 10 which is secured to the plate 4. The inturned end of the deflector 10 projects through a coin port 11.

A magnet 5 is secured to the plate 4 below the coin slot 31. Below the magnet and to one side thereof is mounted a weighted lever 6. If a slug composed of some material acted upon by magnetism is inserted in the slot 31, it will be attracted by the magnet and as it falls by the action of gravity it will be drawn by the magnet to a point where it will fall onto the ledge or shelf 33 and thence will pass out through the discharge opening 34. If the slug is composed of lead or some other non-resilient material it will strike the magnet, will not rebound therefrom and, consequently, as it falls it will strike the lever 6 so near the fulcrum

thereof that it will not tilt the lever and, consequently, it will roll down over the lever and shelf 33 and will be discharged through the opening 34. In like manner spurious coins unaffected by magnetism and too light to tilt the coin lever 6 will also be discharged through the opening 34. If a genuine coin is deposited in the machine, it will strike the magnet 5 and rebound therefrom, falling onto the obliquely-arranged arm 6^a of the coin lever 6, thereby tilting the lever so as to be deflected into the coin slot 35 and thence into the coin receiving notch 9^a of the lever 9.

A manipulation of the button 13 raises the lever 9 against the curved end 8^a of the segment 8, thereby actuating the segment 8 and the segment 27 to tilt the tray 26 to deliver the article from the machine. As the article falls from the tray 26, it is received in a space 32, whence it is removed by the purchaser. While the segment 8 is in normal position, as is shown in Figs. 2 and 3, it rests against the hump 7^a of a spring 7 and thereby depresses the offset end 7^b out of the path of the lower end of the lever 6 to permit the lever to tilt. When, however, the segment 8 has been actuated by the raising of the lever 9 with the coin thereon, the segment is disengaged from the hump 7^a, and thereby permits the offset end 7^b of the spring 7 to be interposed in the path of the lower end of the lever 6. The lever 6 is thus locked in position and hence, if additional coins are inserted in the machine, while it is operating to deliver an article, these coins will pass out the discharge opening 34. When the bottom of the coin resting in the notch 9^a has passed beyond the deflector 10, the segments 8 and 27 have been actuated sufficiently to tilt the tray far enough to deliver the article resting thereon. When the coin passes beyond the end of the deflector 10, the segments 8 and 27 are returned to normal position under the action of the springs 36 and 37. The coin is thereby discharged through the coin port 11 and falls into the coin tray 22.

Having thus described the invention what is claimed as new is:

1. A coin-controlled vending machine comprising a box for containing the articles to be vended, a tiltable tray mounted in the box for supporting the articles, a toothed segment connected therewith, a hinged cover for the box, and coin-controlled mechanism supported in the cover including a notched segment adapted to engage with the toothed segment to tilt the tray to deliver the articles from the machine.

2. A coin-controlled vending machine comprising a tray for supporting the articles to be vended, a toothed segment connected with the tray, a notched segment connected with the toothed segment, a revoluble lever

adapted to be operatively connected with the notched segment by a coin, and means for actuating the lever and means for disconnecting the notched segment and the toothed segment when the vending machine is being filled.

3. A coin-controlled vending machine comprising a box, a tiltable tray mounted in the box for supporting the articles to be vended, a toothed segment connected with the tray, a cover for closing the box, and coin-controlled mechanism supported in the cover including a notched segment adapted to engage the toothed segment, and a revolvable lever adapted to be operatively connected with the notched segment by a coin to actuate the segments to tilt the tray to deliver the articles from the machine the opening of

said door disconnecting the notched segment and the toothed segment.

4. A coin-controlled vending machine comprising a box for containing the articles to be vended, a tray mounted in the box for supporting the articles, a cover for closing the box and provided with a lock with sliding bolt; a slotted flange on the box; and a coin tray carried by the cover; said coin tray having a flanged portion enclosing the lock in the cover and an opening in the flange—the bolt of the lock adapted to be passed through said flanged portion and the flange on the box, to simultaneously lock the tray in the cover and the cover to the box.

In testimony whereof I have signed my name to this specification.

MATTHEW G. O'NEIL.
